FIG. 1.

FIG. 2.

Margaret E. Hostater
Inventor

By *Geo. P. Kimmel.*

Attorney

UNITED STATES PATENT OFFICE.

MARGARET ELONER HOSTATER, OF WESTFIELD, NEW YORK.

DISH-WASHING MACHINE.

1,393,687.

Specification of Letters Patent.

Patented Oct. 11, 1921.

Application filed February 24, 1917. Serial No. 150,775.

To all whom it may concern:

Be it known that I, MARGARET ELONER HOSTATER, a citizen of the United States, and resident of Westfield, in the county of 5 Chautauqua and State of New York, have invented certain new and useful Improvements in Dish-Washing Machines, of which the following is a specification.

This invention relates to an improved dish 10 washing device.

The dominant object of the invention is to provide a dish washing device for receiving soiled dishes therein and rotating the same in a cleansing solution to remove all 15 foreign matter therefrom, whereupon, the same may be removed from the cleansing solution and then rinsed.

Another object of the invention is to provide novel means for receiving the dishes 20 to be cleansed so that the same can be readily removed to allow the cleansing or rinsing solution to drain therefrom.

A further object of the invention is to provide means for rotating the dish receiving means in the cleansing solution, the 25 said means being detachably associated therewith to permit the removal of the same when placing or removing dishes from the receiving means.

30 Other improvements and novel details in the construction and arrangement of parts will be appreciated from the detailed description below, which is to be read in connection with the accompanying drawings 35 forming a part hereof, and wherein I disclose the preferred embodiment of the invention for the purpose of illustration.

In the drawings:

Figure 1 is a vertical section of my improved dish washing device;

Fig. 2 is a top plan of the same with the primary container closure removed; and

Fig. 3 is a fragmental detail in perspective of a portion of one side wall of the primary container.

Similar characters of reference are employed in all of the above described views to indicate corresponding parts.

Referring now more specifically to the 50 several figures of the said drawings, there is provided a primary container 1, the bottom of which is formed concavo-convex and has arranged concentrically thereof a bearing pocket 2. Hand holds 3 are arranged 55 upon the sides of the primary container 1 at substantially diametrically opposite

points, thus, providing means to facilitate the moving of the same from place to place. A cap like closure 4 having a depending annular flange 4^a formed thereon, is adapted 60 to be snugly engaged with the mouth of the primary container 1 and has an outwardly extending flange 4^b and also has formed in the body thereof an opening surrounded by a collar 4^c, the purpose of which will be subsequently apparent. Within the upper extremity of the side walls of the container 1, I form a plurality of oppositely disposed notches or seats 5, the seats being of a depth to extend below the depending flange 4^a and 70 collar 4^c formed upon the closure 4 when the same is arranged over the mouth of the primary container.

Within the primary container 1, I arrange a secondary foraminated container 6, this 75 container being of a size slightly less than that of the primary container but being of a shape complementary thereto in order that the same may be loosely positioned therein. A plurality of legs 7 are arranged 80 upon the bottom of the secondary container 6 while a bearing pintle 8 is arranged concentrically of the bottom and is of less length than the legs 7 and normally received within the bearing pocket 2 formed in the 85 concavo-convex bottom of the primary container. By the peculiar mounting of the secondary container within the primary container, it is evident that the various legs 7 formed upon the bottom of the said secondary container will be maintained in spaced 90 relation from the bottom of the primary container and as a consequence, rotation of the same is permitted. To facilitate handling of the secondary container 6 a plurality 95 of hand pieces 9 are pivotally secured to the sides thereof in proximity of the top of the same, thus, enabling the user to readily grasp the same when removing the secondary container from the cleansing solution, as 100 received by the primary container 1. A plurality of apertured lugs 10 are formed upon the inner surface of the secondary receptacle mouth and receives therein at times, portions of locking lugs 11 as carried upon 105 a closure 12 for the secondary container.

With a view toward providing means whereby the secondary container may be rotated within the primary container to cause the circulation of the cleansing solution through the foraminated side walls of the same into engagement with the dishes 110

contained therein, a cross bar 13 having the opposite ends thereof reduced as at 14 spans the upper end of the primary container 1, the said reduced ends seating within the 5 seat 5 therefor and projecting beyond the side walls of the container, said ends having shoulders at their junctions with said bar which shoulders are designed to engage the inner faces of the outer container adjacent the notches therein to hold the bar against longitudinal movement in the container. A gear 15 is rotatably mounted upon the cross bar and has the shaft therefor extended upwardly and squared as at 16, 10 the said squared portion extending through the openings formed in the primary container closure 4 to allow the engaging of a crank handle 17 therewith. Upon the upper face of the closure 12 there is fixedly 15 mounted a second gear 18, the stub-shaft of which is loosely engaged with a suitable opening formed in the cross bar 13, thus, bracing or rigidifying the gear 18, in order that the same may be constantly maintained 20 in mesh with the gear 15.

Obviously, by rotating the crank handle 17, rotary motion will be imparted to the secondary container 6, hence, the cleansing solution as arranged in the container 1 will 25 be agitated thereby and caused to thoroughly circulate about the various dishes positioned within the said secondary container. When the dishes have been properly cleansed, the crank handle 17 may be readily disengaged 30 from the squared portion 16 of the stub-shaft of the gear 15 and the closure 4 together with the cross bar 13 then removed. The secondary container 6 may be now removed from the primary container and its 35 cleansing solution and placed within or upon a sink or suitable receptacle, whereupon the cleansing solution remaining therein will be permitted to readily drain therefrom. The container 6, when removed, may be evenly 40 supported upon the several legs 7 which, as stated, extend below the pintle 8. The cover 12 may be now removed by slightly turning the same to bring the locking lugs 11 out of engagement with the apertured lugs 10 and 45 pulling the same upward. A rinsing water 50

is then poured over the dishes, thus, rendering the same ready for drying.

To permit the draining of the cleansing solution from the primary container 1, there is formed within the bottom of the same an 55 internally screw threaded opening into which a screw threaded plug 19 is turned.

If desired, the device can be operated by a 60 motor, the handle being removed and suitable gearing substituted therefor.

Still further embodiments of the invention than those herein especially defined may be resorted to as conditions or preference may dictate, as may be in keeping with the hereto appended claim.

I claim:

In a dish washing machine an outer imperforate and an inner perforate container spaced apart and supported to provide for the rotation of the inner container within the outer both being provided with removable closures, the closure of the outer container being flanged and having an opening therein, said container having diametrically opposite notches in its upper edge of a depth 75 greater than the flange of its closure, a cross bar having reduced ends detachably mounted in said notches and projecting beyond the side walls of said outer container, said ends having shoulders at their junctions with said bar which engage the inner face of the outer container adjacent said notches to hold the bar against longitudinal movement, intermeshing gears carried by said cross bar and the closure of the inner container, the journal of the cross bar carried gear extending through the opening in the closure of the outer container and equipped with an actuating handle for rotating the gears to operate the inner container, the flange on the 80 outer container closure bearing on said cross bar to assist in retaining said bar in operative position, the closure snugly fitting the upper end of the outer container above the projecting cross bar ends with its flange 85 resting on said ends to assist in retaining the bar in operative position.

In testimony whereof, I affix my signature hereto.

MARGARET ELONER HOSTATER.
